UNITED STATES PATENT OFFICE.

MOSES P. LITTON, OF SALTVILLE, VIRGINIA.

SAW SET.

Application filed May 8, 1926. Serial No. 107,622.

This invention relates to a sawset.

The object of the invention is the construction of a simple and efficient device for efficiently holding a saw-blade and at the same time setting the teeth thereof.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a view in side elevation of a crosscut sawset constructed in accordance with the present invention, while Figure 2 is a top plan view of the same.

Figure 3 is a sectional view taken on line 3—3, Figure 1 and looking in the direction 20 of the arrows.

Figure 4 is a sectional view taken on line 4—4, Figure 2.

Figure 5 is a perspective view of the guide device.

Figure 6 is a perspective view of the setting plunger.

Figure 7 is a perspective view of the vice plunger.

Figure 8 is a perspective view of an embodiment of the anvil.

Referring to the drawings by numerals, 1 designates the primary handle upon the inner end of which is the integral head 2. In the head 2 is positioned the detachable anvil 3. This anvil 3 is provided with bevelled edges 4 on all sides or edges, whereas in Figure 5, I have shown a modified anvil 3^a, which has a straight edge 8 for the purpose of expediting the removal of the set from the saw when there is too much set in a saw. The anvil 3 is mounted upon the inner end of the anvil adjusting screw 6.

A guide device 7 is in the head 2, this guide device being provided with a threaded shank 8 upon the outer end of which shank is butterfly nut 9. The guide device 7 is provided with an overhanging flange 10 and with an integral depending bifurcated flange 11, in the bifurcation of which works the inner end of setting plunger 12. On shank 8 between head 2 and flange 10 is coil spring 8^a. When the nut 9 is loosened spring 8^a helps to move guide device 7 inwardly, for engaging with the saw teeth. The plunger 12 has a coil spring 13 mounted on the rod like inner end 14 and the outer

end of plunger 12 is provided with a head 15 that is positioned in the lower end of setting plunger fork-link 16; a pin 17 extends through fork-link 16 and head 15 of plunger 12, pivotally fastening the same together. A pin 18 pivotally mounts the straddling end of fork-link 16 upon handle 1.

A setting plunger lever 19 is provided with a downwardly curved inner end 20; this end 20 is pivotally mounted at 21 upon jack-link 22; jack-link 22 is pivotally mounted at 23 upon lugs 24; lugs 24 are integral with handle 1. The lever 19 is provided with an integral curved rearwardly 70 extending heel 25. This heel 25 is adapted to strike against setting plunger screw 26.

A connecting rod 27 is pivotally fastened at 28 to the upper end of fork-link 16, whereas its other end is pivotally connected 75 at 29 to the curved end 20 of the lever 19.

An integral depending yoke 30 is formed upon the handle 1, and pivotally mounted, at 31, upon yoke 30, is a vice plunger handle 32. This handle is provided on its inner end 80 with a pair of upstanding and rearwardly extending ears 32. These ears 32 are adapted to strike against abutment pin 33 to limit the downward or outward swinging movement of handle 32. Between ears 32 is 85 pivotally mounted the flat inner end 34 of the vice plunger 35. This vice plunger 35 is provided with a rodlike outer end 36 which extends through the inner side of head 2 and is adapted to press against the 90 saw-blade 37 (Fig. 1); opposite to outer end 36 is the anvil 3, between which anvil 3 and end 36 is clamped the saw-blade during the setting operation.

A setting screw 38 is mounted upon handle 1 to limit the inward pivotal movement of handle 32, as the clamping action takes place on the sawblade 37. It will be understood that abutment pin 33 will prevent the handle 32 from swinging outward too far. 100

Referring particularly to Figure 8:

In the structure of the anvil 3 (Fig. 1), the anvil in the head 2 has four equal sides, and is bevelled on each side, whereas in Figure 8, I make the (1) side or edge 5 straight 105 and the object of this is to expedite the removal of the set from the saw-blade 37 when there is too much set in the saw.

In operation, I first adjust the setting plunger adjusting screw 26 to gauge wanted. Then I adjust adjusting guide device 7 by turning the butterfly nut 9. By tightening

this nut 9, a long set can be obtained, and by loosening nut 9, a short set from point of tooth can be obtained; the latter is better for hardwood cutting. By giving saw the 5 long set it may be filed several times without resetting. Vice plunger handle 32 operates vice plunger 35 whereby the blade 37 is gripped and kept from springing while setting plunger 12 forces set. By adjusting 10 screw 38 until it clears vice plunger handle 32, the said handle will have a slightly freer movement inwardly to obtain a greater gripping action on the saw-blade.

To remove set from saws that have too 15 much set, first loosen shank 8 by turning nut 9, then adjust screw 38 to gauge wanted, then place the entire device over the teeth of the blade and grip handles 1 and 32 until vice plunger handle 32 rests against screw 20 38. To find gauge desired, use the common "spider," which is a tool used by all saw filers.

While I have described the preferred embodiments of my invention and illustrated 25 the same in the accompanying drawings, certain minor changes or alterations may appear to one skilled in the art to which this invention relates during the extensive manufacture of the same, and I, therefore, reserve the right to make such changes or alterations as shall fairly fall within the scope 30 of the appended claims.

What I claim is:

1. In a crosscut sawset, the combination 35 of a handle provided with a head, a guide device in said head, said guide device comprising an overhanging flange with a depending bifurcated flange, a threaded shank extending from said overhanging flange 40 through said head, a nut on said shank against said head, a setting plunger on the head and working in the bifurcated flange of said guide device, means for operating said setting plunger, and means on the head 45 for clamping a saw-blade therein.

2. In a crosscut sawset, the combination 50 of a handle provided at one end with a head, a setting plunger mounted upon said head, a setting plunger fork-link straddling said handle, means pivotally mounting said straddling portion of the fork-link upon the handle, means pivotally connecting the straddling portion of the fork-link to the 55 setting plunger, a setting plunger lever, said handle provided with upstanding lugs, a jack-link pivotally mounted on said lugs, said setting plunger lever pivotally mounted on the outer end of said jack-link, means pivotally connecting said setting plunger lever 60 and the upper or outer end of said fork-link,

said setting plunger lever provided with a curved rearwardly extending heel, and a screw on said handle and adapted to be engaged by said heel.

3. In a crosscut sawset, the combination 65 of a handle provided with a depending bifurcated head and a depending yoke, a setting plunger and a vice plunger slidably mounted on said head, a vice plunger handle pivotally mounted within said yoke, means 70 pivotally connecting said vice plunger to said vice plunger handle within the yoke, a setting plunger lever pivotally mounted on the first mentioned handle, a fork-link straddling the handle and pivotally connecting to 75 said setting plunger, and a link pivotally connecting said setting plunger lever and said fork-link.

4. In a crosscut sawset, the combination 80 of a handle provided with a bifurcated head, an adjustable guide device mounted upon the head and extending into the bifurcation thereof, a removable anvil in the bifurcation of said head under said guide device, means 85 movably mounted on the head for clamping a saw-blade against the anvil, and means movably mounted on the head and working through a portion of said guide device for bending saw teeth against the anvil.

5. In a crosscut sawset, the combination of 90 a handle provided with a head, said handle provided with an extension, a jack-link pivotally mounted on said extension, a lever pivotally mounted at its inner end upon said jack-link, said lever provided with a rearwardly extending heel, threaded means on the handle engaged by said heel for limiting movement of the lever, teeth bending means on said head, and means connecting said lever to said teeth bending means. 95

6. In a crosscut sawset, the combination 100 of a handle provided with a depending bifurcated head, a threaded shank extending through the top of said head and into its bifurcation, a horizontal flange integral with 105 said threaded shank, a bifurcated flange depending from one edge of said first mentioned flange, a nut on said shank outside of said head, an anvil in the bifurcation of said head contiguous to said bifurcated flange, a setting plunger slidably mounted in one side of said head and extending through the bifurcated flange with said flange straddling the same, and means for operating said 110 setting plunger for bending saw teeth against the anvil. 115

In testimony whereof I hereunto affix my signature.

MOSES P. LITTON.
